DESIGN FOR A FOUNTAIN PEN

Max M. Neuhoff, New York, N. Y.

Application March 2, 1934, Serial No. 50,924

Term of patent 7 years

To all whom it may concern:

Be it known that I, MAX M. NEUHOFF, a citizen of the United States, residing at New York city, in the county of Bronx and State of New York, have invented a new, original, and ornamental Design for Fountain Pens, of which the following is a specification, reference being had to the accompanying drawing, forming part thereof.

In said drawing, Fig. 1 is an elevational view closed and Fig. 2 is an elevational view open of a fountain pen, showing my new design.

I claim:

The ornamental design for a fountain pen, as shown and described.

Dated this 19th day of February, 1934.

MAX M. NEUHOFF.
